[57] CLAIM

The ornamental design for a turnbuckle, or similar article, substantially as shown and described.

DESCRIPTION

FIG. 1 is a perspective view of a turnbuckle, or similar article, showing my new design;

FIG. 2 is a side elevational view thereof, the opposite side being a mirror image thereof;

FIG. 3 is a top view thereof;

FIG. 4 is a bottom view thereof;

FIG. 5 is an end view thereof, the other end having the same appearance; and

FIG. 6 is a cross-section in the plane VI—VI in FIG. 1.
